UNITED STATES PATENT OFFICE.

CHARLES H. BEEMAN, OF NORTH FAIRFAX, VERMONT

DESIGN FOR A POTATO-BAKER.

SPECIFICATION forming part of Design No. 21,597, dated May 31, 1892.

Application filed April 2, 1892. Serial No. 427,643. Term of patent 7 years.

To all whom it may concern:

Be it known that I, CHARLES H. BEEMAN, a citizen of the United States, residing at North Fairfax, Franklin county, Vermont, have invented and produced a new and original Design for a Potato-Baker, &c., of which the following is a specification, reference being had to the accompanying drawing, forming part of this specification, and to letters of reference marked thereon.

The drawing is a perspective view of the baker, which slightly resembles an open-work wire basket or pan. Its bottom is formed of a series of parallel longitudinal rods A, connected at their ends to an encircling hoop B. Each rod has a series of upstanding studs a on its upper edge, the studs on adjoining rods

standing intermediate those on adjoining rods. The adjoining bars A may be connected by transverse pieces C, as shown. Above hoop B is a larger hoop D, connected thereto by inclined side wires E.

The whole utensil resembles a skeleton of a rectangular basket having a studded bottom.

The utensil is especially designed as a potato baker, broiler, &c.

What I claim as new is—

The design for a potato-baker or similar utensil, substantially as herein shown and described.

CHARLES H. BEEMAN.
